Primary Examiner—Bernard Ansher**Assistant Examiner—Prabhakar Deshmukh****Attorney, Agent, or Firm—James & Franklin****[57] CLAIM**

The ornamental design for a display package for bath
accessories, as shown and described.

DESCRIPTION

FIG. 1 is a top perspective view of a display package for
bath accessories showing my new design;

FIG. 2 is a top perspective view thereof, showing undis-
closed sides in FIG. 1; and,

FIG. 3 is an exploded perspective view thereof.
The bottom surface is plain and unornamented.

F I G. 1

FIG. 2
